UNITED STATES PATENT OFFICE.

WILLIAM FRANCIS MCPHEE, OF CHICAGO, ILLINOIS.

BOILER FOR HOT-WATER HEATING PLANTS.

Application filed June 11, 1925. Serial No. 36,476.

My invention relates to improvements in improved boiler for hot water heating plants, and it consists in the combinations, constructions, and arrangements herein described and claimed.

An object of my invention is to provide an improved boiler of the type described by means of which initial circulation in the hot water heating system brought about immediately after establishing a fire in the fire box by generation of steam in a unit of the boiler closely adjacent to the fire in which a small quantity of water is placed.

A further object of my invention is to provide an improved boiler for hot water heating plants of the character described in which vertically disposed chambers are provided in the boiler jacket and which communicate at their lower ends with the inlet 15 openings of the heating units, whereby water admitted to the heating units is taken directly from the top portion of the boiler water jacket where it is at its highest temperature.

A further object of my invention is to provide an improved boiler for hot water heating plants of which the construction is such that the products of combustion must travel along the entire surface of the several heating units before the gases are permitted 20 to escape through the flues.

A further object of my invention is to provide an improved boiler for hot water heating plants in which direct circulation vertically through the units is prevented.

A further object of my invention is to provide a boiler for hot water heating plants in which the possibility of accumulation of minerals on the inner walls of the units is practically precluded due to the absence of 25 cavities, corrugated surfaces, and the like, which ordinarily serve to promote such accumulation.

A further object of my invention is to provide a device of the type described which is simple in construction, durable, and thoroughly practical commercially.

Other objects and advantages will appear in the following specification, and the novel features of the invention will be particularly 30 pointed out in the appended claim.

My invention is illustrated in the accompanying drawing forming part of this application, in which

Figure 1 is a sectional view of an embodiment of my invention,

Figure 2 is a sectional view along the line 2-2 of Fig. 1,

Figure 3 is a sectional view along the line 3-3 of Figure 1,

Figure 4 is a section along the line 4-4 of Figure 1, and

Figure 5 is a sectional view along the line 5-5 of Fig. 1.

In carrying out my invention I make use of a substantially bell-shaped vertical water jacket 1. The water jacket is provided with a passageway 2 therethrough at the upper end, and has an inlet 3 adjacent the lower end.

An oil burner 4 is provided with a deflector plate 5 and is disposed within the inner wall 8 of the jacket. The deflector plate 5 is so constructed as to deflect flames 6 toward the inner wall of the jacket 1.

The water jacket is provided with a pair 75 of auxiliary outlets 7 at the upper end which may be used in certain types of heating systems requiring more than one outlet.

The heating elements of my improved boiler comprise a plurality of relatively thin 80 pancake units having extremely thin side walls. The first of the units is shown at 9 and is connected at diametrically opposite points to the water jacket 1 by the provision of tubular neck members 10.

This unit 9 is substantially annular in contour and its outer peripheral wall 11 just clears the inner wall 8 of the jacket 1 so that expansion of the unit will not injure the jacket but so close as to prevent the passage 90 of the products of combustion between the wall 8 and the unit 9. The central passage of the annulus is shown at 12 and is sufficiently large in diameter to permit the products of combustion from the burner 4 to pass 95 therethrough, having first been deflected from the adjacent wall portions of the wall 8. The unit 9 is so close to the burner 4 as to permit the actual generation of steam therein, which is for the purpose of exciting 100 and starting circulation of water directly through the radiators or other heating devices used with boilers, in a manner hereinafter described.

The unit 9 is connected by means of a pair of diametrically opposed vertical passages 13 which are connected with a similar pair of passages 14 forming a part of the second unit shown at 15 in Figure 1. This unit 15 is constructed of the same thin ma- 111

terial of which the unit 9 is constructed. The unit 15 is substantially three inches less in diameter than the distance from opposite points of the wall 8, so that the products of combustion must pass between the peripheral walls 16 of the unit 15 and the adjacent portions of the wall 8.

5 A third unit 17 is connected by means of connected passages 18 and 19 associated 10 with the units 15 and 17 respectively to the unit 15. From inspection of Figure 3 it will be noted that the passages 19 are disposed substantially 90° from the passages 13. Thus direct circulation of water from 15 the unit 9 to the unit 17 is prevented.

The only difference between the units 9 and 17 is that a passage 20 corresponding to the passage 12 in function through the unit 17 is disposed toward the rear wall of 20 the unit 17, and out of alignment with the passage 12. The outer peripheral wall 21 of the unit 17 lies closely adjacent to the inner wall 8 of the jacket 1 as in the case of the unit 9. The unit 17 is connected by 25 means of vertically extending diametrically opposed passages 22 with a last or upper unit 23. This unit has its outer peripheral wall 24 extending for substantially 270° of its circumference, in close engagement with the 30 adjacent wall 8 of the jacket 1. The remaining 90 degrees being disposed at the forward portion of the unit is set back from the adjacent portions of the wall 8 as shown at 25. Thus the products of combustion 35 passing through the passage 20 at the rear of the unit 17 is deflected from the adjacent wall 8 of the jacket 1 and the rear under surfaces of the unit 23 toward the portion 25 of the unit 23, and thereupon pass over 40 the unit 23 to a flue disposed through the rear portion of the jacket 1 as shown at 26.

A single vertically extending tubular neck 28 is provided and communicates with the upper portion of the unit 23, and extends 45 through the opening 2 in the jacket 1. This tubular neck is threaded as shown at 29 and a lock nut 30 is disposed upon the threaded portion and arranged to bear upon the outer surface of the jacket 1 so that by tightening 50 the nut 30 an upward pull is exerted upon the vertically aligned units 9, 15, 17 and 23. It should be understood of course that suitable packing may be disposed between the portion 30 and the wall of the jacket, so as 55 to prevent the products of combustion from leaking therethrough.

From an inspection of the drawing it will be noted that a pair of vertical compartments are provided on each side of the water jacket 1 by the provision of parallel side walls 30 which open with a bottom wall 31 so as to cause water admitted to the inlet openings of the tubular neck members 10 to be drawn from the top portion of the water jacket. The height of the walls 30 is just

short of the top crown plate of the jacket. The lower end of the compartment is in registration, as shown in Figure 1, with the mouth of the tubular passages 10.

From the foregoing description of the 70 various parts of the device the operation thereof may be readily understood. My improved boiler for hot water heating plants is especially well adapted for use where it is desirable to supply hot water in radiators 75 upon a relatively short notice. The boiler may be successively used in very small installations requiring small quantities of water, or in large installations in which a large number of radiators are employed. 80 In the latter event, the number of units is increased, as well as the volume. The increase in volume is usually effected by increasing the diameter and not the height of 85 the units.

Let us assume that the water system is of 90 normal temperature, and that it is desired to supply hot water to the radiators. In this event, the burner 4 is actuated, causing the flames and the products of combustion 95 thereof to be deflected by the deflector plate 5 toward the wall 8 of the jacket 1. These flames and products of combustion can not pass between the wall 8 and the ends 11 of the unit 9, so they must move toward the 95 center of the combustion chamber along the lower wall of the unit 9 and up through the passage 12.

The course of the flames and hot gases 100 will then follow the lower wall of the unit 15 and up past the peripheral wall 16 of the unit, whereupon the hot gases will rise 105 and be deflected from the adjacent walls of the jacket 1 of the lower wall of the unit 17 toward the rear central portion of the unit 17 and up through the passage 20.

The course of the hot gases and products 110 of combustion will then be toward the rear under surface of the unit 23, whereupon they must continue to the front wall 25 of the unit 23 and pass upwardly over the unit 23 and out of the flue 26. It should be noted that the major portion of the unit 23 lies close to the wall 8 of the jacket 1 while only the forward portion of the wall 25 is away from 115 the wall to permit the passage of gases there-beyond.

Having thus followed the course of the products of combustion, it is evident that 120 practically every portion of the surface of the units is encompassed in hot gases. Therefore nearly all of the heat therefrom may be absorbed by the water within the units.

From inspection of Figure 1 it will be 125 noted that the unit 9 is relatively close to the burner 4. The walls of this unit as well as the remaining units, have been described as relatively thin. My object in providing especially thin walls is to permit the trans-

mission of as much heat as possible there-through. Thus heat transmitted to the water within the unit 9 is in such quantities as to cause a generation of steam therein.

5 This steam must rise and does so passing through the aligned passages 13 and 14 of the units 9 and 15 respectively, thus exciting circulation of water through the units. The outlet 29 is connected directly with the main 10 feed pipe to the radiators. It is obvious that water from the boilers must circulate through the radiators and supply heat in the vicinity of the radiators.

In Figure 1 I have shown an auxiliary 15 outlet 7 for the jacket 1 which may be used where more than one outlet is desired, or a connection to the pipe 29 if circulation should prove to be too rapid.

All water admitted to the units must pass 20 through the vertical compartments formed by the merger of the vertical side walls 30 and bottom walls 31, which means, of course, that water admitted to the unit is drawn from the top of the water jacket and not 25 from the surrounding portions of the water jacket in the vicinity of the tubular inlets 10.

This construction greatly facilitates the continuous operation of the system, and affords a practically constant supply of hot 30 water. The water at the lower portion of the jacket is heated principally by conduc-

tion and by merger with the warmer water at the top.

I claim:

A boiler for hot water heating plants 35 comprising a combustion chamber, a water jacket enclosing said combustion chamber and having a top arcuate-shaped in cross section, the water jacket being of uniform thickness throughout, a plurality of water 40 heating units disposed in said combustion chamber, water passageways disposed in said water jacket having their inlet openings disposed adjacent to the top of the water jacket, and having their outlet openings communi- 45 cating with the lowermost heating unit, a cold water inlet pipe for said water jacket communicating with the water jacket adjacent to the bottom thereof, water conduits connecting adjacent heating units together, 50 said water conduits being staggered with respect to each other for causing the entire volume of water within the heating units to flow upwardly as the water is heated, the uppermost heating unit having a conical- 55 shaped outlet passageway disposed in the center of the heating unit, whereby all of the water in the uppermost heating unit will pass through said conical-shaped passageway, and an outlet pipe connected to said outlet pasageway.

WILLIAM FRANCIS MCPHEE.
